US0D1103339S

(12) **United States Design Patent** (10) **Patent No.:** **US D1,103,339 S**
(45) **Date of Patent:** **** Nov. 25, 2025**

(54) **LIQUID FEEDER**

(71) Applicant: **THINK GREEN LIMITED**, Auckland (NZ)

(72) Inventor: **Shuting Zhang**, Auckland (NZ)

(73) Assignee: **THINK GREEN LIMITED**, Auckland (NZ)

(**) Term: **15 Years**

(21) Appl. No.: **29/948,820**

(22) Filed: **Jun. 24, 2024**

(30) **Foreign Application Priority Data**

May 10, 2024 (CN) 202430274341.2

(57) **CLAIM**

The ornamental design for a liquid feeder substantially as shown and described.

DESCRIPTION

FIG. 1 is a Top Front Right Side Isometric view of the liquid feeder of the present invention;

FIG. 2 is a Bottom Rear Left Side Isometric view thereof;

FIG. 3 is a Front elevation view thereof;

FIG. 4 is a Rear elevation view thereof;

FIG. 5 is a Left Side elevation view thereof;

FIG. 6 is a Right Side elevation view thereof;

FIG. 7 is a Top plan view thereof; and,

FIG. 8 is a Bottom plan view thereof.

1 Claim, 5 Drawing Sheets
